GOLF CLUB SHAFT

William L. Wetliaufer, Buffalo, N. Y.

Application April 11, 1938, Serial No. 201,258

11 Claims. (Cl. 273—80)

This invention relates to improvements in golf club shafts of the metal tube type.

One object of the invention is to simplify the manufacture of such shafts.

5. A further object is to provide a shaft which is of a substantially uniform flexibility around its axis.

A still further object is to provide a shaft which is so designed that its flexibility may be varied to 10 meet the requirements of the particular player.

The invention is illustrated in the accompanying drawings in which:

Figure 1 is a perspective view of a golf club having a shaft which embodies the invention.

15. Figure 2 is an enlarged fragmentary perspective of the said shaft.

Figures 3 and 4 are transverse sections taken along lines 3—3 and 4—4, respectively, of Figure 2.

20. Figure 5 is a fragmentary view of the blank from which the shaft is formed.

Figure 6 is a similar view of the said blank at a further stage of development.

25. Figure 7 is an enlarged fragmentary section taken along line 7—7 of Figure 6.

Figure 8 is a fragmentary section taken along line 8—8 of Figure 2.

Figure 9 is a section taken along line 9—9 of Figure 6 and shows the shape of the blank at 30 an intermediate stage of the tube forming operation.

Figure 10 is a section similar to Figure 9 showing the blank after completion of the tube forming operation.

35. Figure 11 is a perspective view of one of the bands which are utilized to control the flexibility of the shaft.

Figure 12 is an end view of the ring which is employed to hold the said band against axial 40 placement.

Figure 13 is a view similar to Figure 2 and illustrates a modified form of shaft.

Figure 14 is a fragmentary view in plan of the blank from which the said shaft is produced.

45. Figure 14a is a similar view of the blank at a further stage of its development.

Figure 15 is a transverse section taken along line 15—15 of Figure 13.

50. Figure 16 is a section similar to Figure 15 and shows the shaft just prior to the final stage of development.

Figure 17 is an enlarged fragmentary section taken along line 17—17 of Figure 14a.

55. Figure 18 is a view similar to Figure 13 and shows another embodiment of the invention.

Figure 19 is a fragmentary view in plan of the blank from which the shaft is produced.

Figure 20 is a transverse section taken along line 20—20 of Figure 18.

Figure 21 is a view similar to Figure 20 and 5 shows the shaft just prior to its final stage of development.

Figure 22 is a perspective view of a modified form of the shaft shown in Figure 2.

Figure 23 is a fragmentary view in plan of one 10 of the blank sections from which the said shaft is produced.

Figure 23a is a similar view of the said blank section at a further stage of its development.

Figure 24 is a transverse section taken along 15 line 24—24 of Figure 22.

Figures 25 and 26 are sections similar to Figure 24 showing the blank sections as they appear at intermediate stages of the development of the 20 shaft.

Figure 27 is an enlarged fragmentary section taken along line 27—27 of Figure 23a.

Figure 28 is a view similar to Figure 22 showing a further modified form of the shaft.

Figures 29 and 30 are fragmentary perspectives 25 views of the blank sections which are employed to produce the said shaft.

Figure 31 is a fragmentary section taken along line 31—31 of Figure 28.

The golf club which is illustrated in Figure 1 30 includes a shaft 35, a head 36 and a sleeve 37 which encases that portion of the shaft which is grasped in the hands of the player, the said shaft being tubular in cross-section and tapering in conventional manner from the end which carries 35 the sleeve toward the end which carries the head.

In accordance with the invention the shaft 35 is produced from a sheet metal blank 38 (Figure 5). The latter is in the form of an elongated strip (which is slightly tapered) and is notched along one edge as indicated at 39 to provide projections 40 which are generally hexagonal in shape and along the opposite edge as indicated at 41 to provide projections 42. The 40 latter conform in shape to and are located opposite the notches 39 while the projections 40 conform in shape to and are located opposite the notches 41. Tongues 43 are formed at the outer ends of the projections 40 and 42, the projections 40 being notched at their sides as indicated at 44. Perforations 45 are formed along each side of the blank 38, the said perforations being located along lines which connect the bases of the two series of projections. 55

The invention contemplates the formation of the blank 38 into a tube. During this operation the projections 40 are caused to enter the notches 41 while the projections 42 are caused to enter the notches 39. In order to facilitate entry of the said projections into the said notches, the tongues 43 are preferably first bent at right angles to the body of the blank as best shown in Figures 6 and 7. Hence upon completion of the tube forming operation the tongues 43 extend toward the center of the tube (see Figure 10). Thereafter the said tongues are again bent, as illustrated in Figure 4, so that they engage under the abutting edges of the blank. The tube, therefore, will retain its shape, the projections 40 and 42 interlocking with one another and being held in such relation by the tongues 43. The construction described has the advantage that it provides a shaft having a flexibility which is substantially uniform around its axis.

Means is provided for varying the flexibility of the shaft so that the club may be adapted to the requirements of the particular player. To this end bands 46 are arranged upon the said shaft at spaced intervals. Preferably the said bands are tapered slightly to conform to the taper of the shaft and are adjustable along the latter to increase or decrease the pressure with which the abutting edges of the projections 40 and 42 engage one another. The bands are secured in the desired positions by resilient rings 47 which fit around the shaft and which are formed with inwardly bent ends 47a which may be inserted in either the notches 44 or the perforations 45. The tendency of bands 46 is to slip toward the small end of the shaft. Hence by arranging the rings 47 between them and the end of the shaft which carries the head 36 the bands may be caused to remain in the desired positions.

It will be apparent that adjustment of the bands toward the large end of the shaft increases the pressure with which the abutting edges of the projections 40 and 42 engage one another and hence a greater resistance to relative movement between said edges is offered. The shaft is thus rendered less flexible. On the other hand adjustment of the bands 46 toward the small end of the shaft reduces the pressure with which the abutting edges of the projections 40 and 42 engage one another and hence a less resistance to relative movement between the said edges is offered. The shaft in this case is rendered more flexible. In this connection it is to be understood that the bands 46 control the flexibility of a predetermined section of the shaft and hence in their adjustment in the manner described the abutting edges of the projections 40 and 42 of certain sections of the shaft may be caused to engage one another with a different pressure than the abutting edges of the projections of other of the sections of the said shaft. In other words the bands 46 are not only adjustable to vary flexibility of the shaft throughout its entire length but they are also adjustable to vary the flexibility of a particular section of the said shaft.

A modified form of shaft is illustrated in Figure 13. In this embodiment the said shaft is produced from a sheet metal blank 48. The latter is in the form of a strip and is notched along one side as indicated at 49 to provide projections 50 and along the opposite side as indicated at 51 to provide projections 52. The projections in this embodiment have five sides. However, they conform in shape to the oppositely located

notches and are formed at their outer ends to provide tongues 53. The latter are bent at right angles (see Figures 14a and 17) prior to the operation in which the blank is formed into a tube and after such operation are bent so that they engage the under sides of the abutting edges of the blank as best shown in Figure 15. Bands such as indicated at 54 are preferably arranged upon the shaft in order to control its flexibility, the said bands being adjusted along the shaft until the pressure with which the abutting edges of the projections 50 and 52 engage one another is such that the desired degree of flexibility is attained. The bands 54 may then be soldered or otherwise secured to the shaft in the positions to which they are adjusted.

In the embodiment of the invention illustrated in Figure 18 the shaft is produced from a sheet metal blank 55 (Figure 19) which is notched along opposite sides as indicated at 56 to provide pointed projections 57, the projections along one side being located opposite the notches along the opposite side. During the operation in which the blank 55 is formed into a tube the projections are bent at their bases as best shown in Figure 21, the shoulders 58 which are thus provided fitting against those portions of the opposite edge of the blank which are located between the bases of the co-operating projections. Thereafter the projections 57 are preferably bent so that they fit conformably against the inner wall of the tube as illustrated in Figure 20. Bands such as indicated at 59 are arranged at spaced intervals along the shaft and hold the latter in its tubular shape. Each of the said bands is adjustable axially of the shaft in order to control the flexibility of the latter. For this purpose an end of the said band is formed to provide a cam 60. The latter engages a cam 61 which is formed upon the adjacent end of a collar 62, the said collar having a circumferentially extending slot 63 and being rotatable upon the shaft. A screw 64 which is carried by the said shaft extends through the slot 63 and permits rotative movement of the collar 62 while preventing its movement axially of the shaft. It will be apparent that owing to the taper of the shaft the band 59 will remain in engagement with the collar 62. Thus upon rotation of the said collar in a clockwise direction the band 59 is moved toward the large end of the shaft to decrease the flexibility of the latter while rotation of the said collar in a counter-clockwise direction will permit the band 59 to move toward the small end of the shaft to increase its flexibility, it being understood that the screw 64 is loosened to permit such adjustments and tightened to lock the parts in their new positions when such adjustments have been completed.

In the embodiment of the invention illustrated in Figure 22 the shaft is produced from two sheet metal blanks such as indicated at 65 (Figure 23), each of the said blanks being notched along opposite sides as at 66 to provide projections 67 which, similarly to the embodiments shown in Figures 1 and 13, have undercut sides. The projections on each of the blanks conform in shape to notches in the other and are formed at their outer ends with tongues 68. After formation of the projections 67 the said tongues are bent substantially at right angles as best shown in Figures 23a and 27. Thereafter the blanks 65 are formed into semi-cylinders (Figure 25) which are then assembled so that the projections of each fit in the notches of the other (Figure 26).

Upon completion of this operation the tongues 68 of each semi-cylinder are bent as shown in Figure 24 so that they engage the marginal edge of the companion semi-cylinder, whereby to hold the said parts together. Bands such as indicated at 69 are arranged at spaced intervals along the shaft. The said bands are soldered or otherwise secured in the desired positions and are available to impart the desired flexibility to the shaft.

10 The shaft illustrated in Figure 28 consists of two semi-cylinders 70 and 71. The former (Figure 29) is notched along its opposite edges as indicated at 72 to provide spaced projections 73 which are bent inwardly. The semi-cylinder 71 (Figure 30) is notched along its opposite edges as at 74 to provide spaced projections 75 which are bent inwardly, one end of each of the said projections being bent at right angles to provide a tongue 76. In assembling the semi-cylinders 70

15 and 71 they are arranged so that the projections 73 fit against the projections 75 with the tongues 76 extending through the notches 72. When the said parts are arranged as described the tongues 76 are bent over the projections 73 as best shown in Figure 31. Bands such as are indicated at 77

20 are arranged at spaced intervals along the shaft, the said bands being rotatable on said shaft. One end of each of the said bands is formed to provide a cam 78. The latter engages a pin 79

25 which is carried by the semi-cylinder 71 and owing to the taper of the shaft remains in engagement with the said pin. It will be apparent that when the band 77 is rotated in one direction the pin 79 causes it to move toward the large end of

30 the shaft while when it is rotated in the opposite direction the said pin permits the band to move toward the small end of the shaft. Thus the bands 77 may be moved lengthwise of the shaft to adjust its flexibility in accordance with

35 the requirements of the particular player. Preferably the cam 78 is serrated as indicated at 80 to provide indentations which the pin 79 enters to lock the band 77 in the position to which it is adjusted. Openings 81 may be formed at diametrically opposed points in the said band to accommodate the prongs of the tool which is employed to make the adjustments described.

The shafts of the various embodiments illustrated are formed from blanks which are produced from metal sheets in simple die-stamping operations. The cost of manufacture is, therefore, low. In each case also the abutting edges of the blank are utilized to control the flexibility of the shaft. The said edges, however, are so formed that they do not stiffen or reinforce substantially the shaft along the joint which they define. The shaft, therefore, is of a substantially uniform flexibility around its axis.

I claim as my invention:

1. A golf club shaft comprising a sheet metal tube, said tube having a longitudinally extending joint, the edges which define said joint being notched to provide projections which interlock with one another and means which encircles said tube and which causes the abutting edges of said projections to engage one another with a pressure which will impart the desired degree of flexibility to the tube by controlling relative movement between the abutting edges of said projections.
2. A golf club shaft comprising a sheet metal tube, said tube having a longitudinally extending joint, the edges which define said joint being notched to provide projections which interlock with one another, means for holding said edges so as to maintain the interlocking relation be-

tween said projections and a band which encircles said tube and which causes the abutting edges of said projections to engage one another with a pressure which will impart the desired degree of flexibility to the tube by controlling relative movement between the abutting edges of said projections.

3. A golf club shaft comprising a sheet metal tube, said tube having a longitudinally extending joint, the edges which define said joint being notched to provide projections which interlock with one another and means which encircles said tube and which causes the abutting edges of said projections to engage one another with a pressure which will impart the desired degree of flexibility to the tube by controlling relative movement between the abutting edges of said projections, said means being adjustable to vary the flexibility of said tube.

4. A golf club shaft comprising a tapered sheet metal tube, said tube having a longitudinally extending joint, the edges which define said joint being notched to provide projections which interlock with one another, a band which encircles said tube and which causes the abutting edges of said projections to engage one another with a pressure which will impart the desired degree of flexibility to the tube by controlling relative movement between the abutting edges of said projections, said band being adjustable axially of said tube to vary its flexibility and means for securing said band against axial movement in the position to which it is adjusted.

5. A golf club shaft comprising a tapered sheet metal tube, said tube having a longitudinally extending joint, the edges which define said joint being notched to provide projections which have undercut sides and which interlock with one another, tongues formed on the outer ends of said projections which engage under said edges to maintain the interlocking relation between said projections and a band which encircles said tube and which causes the abutting edges of said projections to engage one another with a pressure which will impart the desired degree of flexibility to the tube by controlling relative movement between the abutting edges of said projections, said band being adjustable axially of said shaft to vary its flexibility.

6. A golf club shaft comprising an elongated sheet metal strip which is notched along its longitudinal edges to provide two linear series of projections and which is so formed that the projections of one series interlock with those of the other series and means which encircles said tube and which causes the abutting edges of said projections to engage one another with a pressure which will impart the desired degree of flexibility to the tube by controlling relative movement between the abutting edges of said projections.

7. A golf club shaft comprising an elongated tapered sheet metal strip which is notched along its longitudinal edges to provide two linear series of projections, the projections of each series having undercut sides and conforming in shape to the notches defined by the companion series of projections, said strip being formed into a tube so that the projections of one series interlock with those of the other series, tongues formed upon the outer ends of the said projections which engage under the opposite edges of said strip to maintain the interlocking relation between said projections, a band which encircles said tube and which causes the abutting edges of said projections to engage one another with a pressure

- which will impart the desired degree of flexibility to the tube by controlling relative movement between the abutting edges of said projections, said band being adjustable axially of said shaft to vary its flexibility and means for securing said band in the position to which it is adjusted. 5
8. A golf club shaft comprising a tapered sheet metal tube, said tube being formed with a longitudinal series of apertures and having a longitudinally extending joint, the edges which define 10 said joint being notched to provide projections which interlock with one another, a band which encircles said tube and which imparts to it the desired degree of flexibility to the tube by controlling relative movement between the abutting edges of said projections, said band being adjustable axially of said tube to vary its flexibility and a resilient ring for securing said band in the position to which it is adjusted, said ring having a laterally extending end which is adapted to 15 be inserted into one of said apertures. 20
9. A golf club shaft comprising a tapered sheet metal tube, said tube having a longitudinally extending joint, the edges which define said joint being notched to provide projections which interlock with one another, a band which encircles 25 said tube and which causes the abutting edges of said projections to engage one another with a pressure which will impart the desired degree of flexibility to the tube by controlling relative movement between the abutting edges of said projections, said band being formed at one end to provide a cam, a collar which is arranged on said shaft and which is formed to provide a cam which engages said first mentioned cam, said collar being formed with a circumferential slot and a screw carried by said tube which extends through 30 35
- said slot, said screw when loosened being adapted to permit rotary movement of said collar to effect movement of said band axially of said shaft to vary the flexibility of the latter. 5
10. A golf club shaft comprising a tapered sheet metal tube, said tube having a longitudinally extending joint, the edges which define said joint being notched to provide projections which interlock with one another, a laterally extending projection which is provided upon said tube and a band which encircles said tube and which causes the abutting edges of said projections to engage one another with a pressure which will impart the desired degree of flexibility to the tube by controlling relative movement between the abutting edges of said projections, said band being adjustable axially of said shaft to vary its flexibility and being formed to provide a cam which engages said laterally extending projection, whereby axial movement of said band in the desired direction may be effected by rotating it. 10 15 20
11. A golf club shaft comprising a sheet metal tube, said tube having a longitudinally extending joint, the edges which define said joint being notched to provide projections which are bent inwardly toward the center of said tube and which fit against one another, the ends of certain of said projections being bent over the ends of other of said projections so as to secure the said edges together and a band which encircles said tube and which causes the abutting edges of said projections to engage one another with a pressure which will impart the desired degree of flexibility to the tube by controlling relative movement between the abutting edges of said projections. 25 30 35

WILLIAM L. WETTLAUFER.
